US00D713028S

(12) **United States Design Patent**
Yevmenenko

(10) **Patent No.:** **US D713,028 S**
(45) **Date of Patent:** **** Sep. 9, 2014**

(54) **SYRINGE PLUNGER ROD**

(75) Inventor: **Yan Yevmenenko**, New York, NY (US)

(73) Assignee: **Becton, Dickinson and Company**,
Franklin Lakes, NJ (US)

(**) Term: **14 Years**

(21) Appl. No.: **29/405,693**

(22) Filed: **Nov. 4, 2011**

(51) **LOC (10) Cl.** 24-02

(52) **U.S. Cl.**

USPC **D24/130**

(58) **Field of Classification Search**

USPC D24/112, 127, 130; 604/218, 232, 224,
604/228, 110, 195; 222/390

See application file for complete search history.

(57) **CLAIM**

The ornamental designs for a syringe plunger rod, substantially as shown and described.

DESCRIPTION

FIG. 1 is a top right rear perspective view of a first embodiment of a syringe plunger rod;

FIG. 2 is a right side elevation view thereof, the top plan view being identical;

FIG. 3 is a left side elevation view thereof, the bottom plan view being identical;

FIG. 4 is a rear elevation view thereof;

FIG. 5 is a front elevation view thereof;

FIG. 6 is a cross-sectional view thereof viewed along axis 6 of FIG. 4;

FIG. 7 is a top right rear perspective view of a second embodiment of a syringe plunger rod;

FIG. 8 is a right side elevation view thereof, the top plan view being identical;

FIG. 9 is a left side elevation view thereof, the bottom plan view being identical;

FIG. 10 is a rear elevation view thereof;

FIG. 11 is a front elevation view thereof; and,

FIG. 12 is a cross-sectional view thereof viewed along axis 12 of FIG. 10.

The broken line showing in FIGS. 1-6 is for the purpose of illustrating portions of the article and form no part of the claimed design.

1 Claim, 8 Drawing Sheets
